UNITED STATES PATENT OFFICE.

THOMAS J. WILLIAMS, OF OZARK, MISSOURI.

CAR-COUPING.

SPECIFICATION forming part of Letters Patent No. 350,178, dated October 5, 1886.

Application filed August 16, 1886. Serial No. 210,963. (No model.)

To all whom it may concern:

Be it known that I, THOMAS J. WILLIAMS, a citizen of the United States, residing at Ozark, in the county of Christian and State of Missouri, have invented certain new and useful Improvements in Car-Couplings; and I do hereby declare the following to be a full, clear, and exact description of the invention, such as will enable others skilled in the art to which it applies to make and use the same.

My invention relates to improvements in car couplings, the object of which is to provide a cheap, simple, durable, and convenient device for coupling and uncoupling cars without going between them. These objects I attain by means of the device illustrated in the accompanying drawings, forming a part of this specification, in which—

Figure 1 is a view in elevation of the device. Fig. 2 is a longitudinal vertical section of the same on the line *xx*. Fig. 3 is a detail of the coupling-link.

Similar letters of reference indicate corresponding parts in the several figures.

A is the end of an ordinary box-car, and is provided with a draw-head, B. Said draw-head is made of any suitable material and in one piece, and is preferably provided with a square chamber, O, in its center. Said draw-head is secured to the car by any suitable means. Draw-head B is provided with a hole, b, for receiving a pin, F. Said pin F is made so as to work easily up and down, and is provided with a spring, G. Spring G is for holding the pin F firmly in place, to prevent it from bounding or working up out when the train is in motion; but the pin may be raised up out of the hole b far enough to permit the coupling-link F' to come out by pressing the spring G up against the top of support W. W is a support secured by any suitable means to the top of draw-head B. Support W is provided at its top with a collar, w². Said collar is provided with a hinged joint, R, by which it is hinged to the top of support W, and at the other side of it is provided with a suitable catch for holding the collar firmly around the top of pin F, thus supporting it firmly in place as it works up and down, so that the pin F may be taken out with ease when desired. The front end of draw-head B is made so as to be flaring or bevelled outward in all directions from the center of the draw-head, so that when the link in the car to be coupled strikes the draw-head it will be guided to the center of the draw-head so as to couple. Draw-head B is also provided with a head-block, H. Said head-block H is provided with a head, h⁴. Said head is provided with a notch, h², for receiving the end of link F', and is made so as to fit over the end of said link. Head-block H is also provided with an arm, h³, to serve as a guide for the head-block. Arm h³ is provided with a spring, h, one end of which rests against the inner back part of chamber O, and the other end rests against the shoulder h⁵ of head-block H, and is for holding the head-block forward against shoulder b³ of draw-head B. Draw-head B is also provided with an opening, b⁴, into chamber O from the top side of the draw-head, so that the head-block may be easily removed to be repaired or a new one put in. Said opening is covered by any suitable means, as by means of a plate, P, which may be secured in place by any desired means, or by means of being dovetailed in and then fastened in position by means of thumb-screws. Attached to the upper end of pin F is a chain, N, or other device for drawing out pin F. This chain passes over a cam, C, and is attached to it. Cam C is pivoted or fastened to shaft L by any suitable means. Shaft L is secured to the end of the car by suitable bearings, M, so that it may be turned easily. The ends of shaft L are provided with lever L², so that the car may be uncoupled by means of the lever L² without going between the cars. The chain that extends up over the top of cam C passes on up over a similar cam, C', and then upon the top of the car, and is provided with a lever, K, at its end, which is hinged at its lower end to the top of the car, and is for uncoupling the cars from the top of the car. F' is a link, and is provided with an oblong hole in its ends for receiving the pin F.

My invention is operated by pressing forward on one of the levers K or L², thus drawing on chain N, and by so doing it draws the pin F up out of the way of the link F', and the link is thrown out by means of the spring h throwing the head-block H forward against the shoulder b³, so that when the levers are allowed to be free the pin F will press down upon

and rest upon the top side of head-block H. Thus the pin is held up out of the way of the link, so that when the link F' strikes against the head-block H it will drive the head-block 5 back, and the pin F is thrown down through the hole in the link by means of the spring G, and thus couple the cars.

Having thus described my invention, what I claim as new, and desire to secure by Letters 10 Patent, is—

1. In a car-coupling, a draw-head, B, provided with a head-block, H, which is provided with a spring, h, combined with a pin, F, having a spring, G, and a support, W, having a 15 hinged collar, w², substantially as shown and described.

2. The combination of a hollow draw-head,

B, having a head-block, H, provided with a spring, h, and a pin, F, having a support, W, and a spring, G, with a chain, N, provided 20 with cams C C', and levers L² K, substantially as shown and described.

3. The combination, with levers L² and K, having a chain provided with cams C C', of a pin, F, provided with a spring, G, and a support, W, a hollow draw-head, B, provided with 25 a head-block, H, having a spring, h, and link F', substantially as shown and described.

In testimony whereof I affix my signature in presence of two witnesses.

THOMAS J. WILLIAMS.
